US0D1071321S

(12) **United States Design Patent** (10) **Patent No.:** **US D1,071,321 S**
(45) **Date of Patent:** **** Apr. 15, 2025**

(54) **ELECTRONIC ATOMIZATION DEVICE**

(71) Applicant: **ALD GROUP LIMITED**, Guangdong (CN)

(72) Inventor: **Minbo Xiang**, Guangdong (CN)

(73) Assignee: **ALD GROUP LIMITED**, Shenzhen (CN)

(**) Term: **15 Years**

(21) Appl. No.: **29/894,700**

(22) Filed: **Jun. 13, 2023**

(30) **Foreign Application Priority Data**

Dec. 13, 2022 (CN) 202230834764.6

(51) **LOC (15) Cl.** **27-07**

(52) **U.S. Cl.** ..... **USPC D27/162**

(57) **CLAIM**

The ornamental design for an electronic atomization device as shown and described.

DESCRIPTION

FIG. 1 is a front, right, and top side perspective view of an electronic atomization device according to a first embodiment;

FIG. 2 is a rear, left, and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, and top side perspective view of an electronic atomization device according to a second embodiment;

FIG. 10 is a rear, left, and bottom side perspective view of the second embodiment;

FIG. 11 is a front elevation view of the second embodiment;

FIG. 12 is a rear elevation view of the second embodiment;

FIG. 13 is a left side elevation view of the second embodiment;

FIG. 14 is a right side elevation view of the second embodiment;

FIG. 15 is a top plan view of the second embodiment; and, FIG. 16 is a bottom plan view of the second embodiment. The broken lines are included to show features that form no part of the claimed design.
